DESIGN FOR A BOX FOR COSMETICS
OR THE LIKE

Georges Baud, Paris, France

Application August 21, 1946, Serial No. 132,709

Term of patent 14 years

(Cl. D58—12)

To all whom it may concern:

Be it known that I, Georges Baud, a citizen of the Republic of France, residing at Paris, France, have invented a new, original, and ornamental Design for a Box for Cosmetics or the like, of which the following is a specification, reference being had to the accompanying drawing, forming part thereof, in which

Fig. 1 is a perspective view of a box for cosmetics or the like, in opened position, showing my new design; and

Fig. 2 is a perspective view thereof, in closed position.

I claim:

The ornamental design for a box for cosmetics or the like, substantially as shown.

GEORGES BAUD.
